MACHINE FOR ARMORING CABLES.

1,230,008.

Specification of Letters Patent. Patented June 12, 1917.

Application filed July 1, 1915. Serial No. 37,536.

To all whom it may concern:

Be it known that we, GEORGE E. MIRFIELD and FRANK H. NULLMEYER, citizens of the United States, residing at Youngstown, in the county of Mahoning and State of Ohio, have invented certain new and useful Improvements in Machines for Armoring Cables, of which the following is a specification.

10 The present invention relates to a machine for placing coils of wire around an electric cable for the purpose of inclosing the same and protecting it.

15 One of the objects of the invention is to provide a machine in which the cable will be moved longitudinally and at the same time given rotary movement about its longitudinal axis.

20 A further object of the invention is to provide means for feeding wires into position to wrap around the cable while the cable is being fed through the machine.

25 A further object of the invention is to provide an upper or supply drum and a lower or receiving drum for the cable, and to revolve these drums about their axes and also give to them a rotary movement about a center at right angles to their axes.

30 A further object of the invention is to provide means for enabling a slippage between the lower or receiving drum and the means for rotating the same in accordance with the amount of material wound thereon.

35 A further object of the invention is to provide means which can be actuated by the operator for varying the friction or tension upon certain of the operating parts of the receiving reel to allow of a greater or less slippage of the reel with respect to the means for driving it.

40 The invention further consists in the features of construction and combination of parts hereinafter described and claimed.

In the drawings:

45 Fig. 1 is a side view of the machine of the present invention;

Fig. 2 is a face view of the parts shown in Fig. 1;

Fig. 3 is a plan view of said machine;

50 Fig. 4 is a section on line 4—4 of Fig. 1, looking in the direction of the arrows;

Fig. 5 is a detail of the means for applying friction to certain portions of the mechanism for driving the receiving reel;

Fig. 6 is an enlarged side view of the gear connection for rotating the receiving reel;

Fig. 7 is a section on line 7—7 of Fig. 6;

Fig. 8 is a side view on an enlarged scale of the feeding rolls for the wire and the dies for coiling the wire together with the means for driving the feed rolls; and

Fig. 9 is a section taken on line 9—9 of Fig. 8, looking in the direction of the arrows.

55 In the art to which the present invention relates, the object to be accomplished by machines of this type is to coil a double layer of wire about a cable with the outer layer breaking joints with the inner layer.

60 In the machine of the present invention 70 a double coiling of the wire is effected; that is to say, two wires simultaneously coiled for the inner layer and two wires simultaneously coiled for the outer layer. This is to add strength to the complete product. In 75 carrying out the purpose to be accomplished by the operation of the machine, the cable is rotated about its longitudinal center in place of the dies and wire feeding mechanism being rotated about the cable.

80 Referring now to the drawings, wherein is shown one form of machine made in accordance with the present invention, said machine consists of a frame 10 of any suitable construction, and the main portions of 85 the machine, speaking in a general sense, are an upper reel 11, which may be termed the supply reel, a lower reel 12, which may be termed the receiving reel, a series of feed rolls referred to generally as the feed mechanism 13, and a series of die members referred to generally as the die mechanism 14.

90 The upper reel 11 is composed of the usual reel member mounted to revolve within suitable bearings 15 on arms 15^a of a frame or 95 cage 16. The frame is of U-shaped formation with a lower hub 17 mounted to revolve in a suitable bearing 18, and attached to this hub is a gear 19, meshing with a gear 20, which latter gear is revolved by a 100 bevel gear 21, with which meshes a bevel gear 22, on a main drive shaft 23, and this

drive shaft is operated by means of the usual fast and loose pulleys 24. As the shaft 23 is revolved, through the instrumentalities of the gears 22, 21, 20 and 19, the 5 cage or frame 15 is revolved and this, as will be understood from the drawings, revolves the reel 11 about a center extending at right angles to the center of the trunnions of the reel member which are mounted 10 within the bearings 15.

The gears 21 and 20 are secured to a vertical shaft 25 upon the lower end of which is a gear 26 meshing with a gear 27. This latter gear is secured to a shaft 28, which is 15 connected to a hub or collar 29 on the lower portion of the frame 30, which frame carries the lower or receiving reel 12. The reel 12 is provided with trunnions 31 which are mounted to revolve in bearings 32, in 20 the arms 33 of the frame 30, and the upper ends of these arms revolve within a bearing 34 secured to the frame 10.

Through the instrumentalities of the shaft 25, gear 26, and gear 27, the frame 25 30, which carries the reel 12, is revolved about a center extending at right angles to the center of rotation of the trunnions 31. There is thus established a synchronized drive between the reels 11 and reels 12 so 30 that they are both simultaneously revolved about a center extending at right angles to their center of rotation. It is thus obvious that as the cable passes from the supply reel onto the receiving reel it is revolved 35 about its longitudinal center.

Means must be provided for properly driving the receiving reel 12 to revolve it about the trunnions 31 as a center of rotation, so that the cable may be drawn from 40 the supply reel and wound onto the receiving reel by a longitudinal movement through the machine. The means which are illustrated to accomplish this driving consists of a worm screw 35 fastened to a sleeve 36 which is mounted upon the shaft 28 and to 45 this sleeve is connected or joined a grooved wheel 37. The sleeve 36 and the grooved wheel 37 are affixed to the shaft 28 with a tight fit so that under normal conditions 50 they revolve simultaneously with said shaft, but in case of the coil of cable upon the receiving reel becoming so large that each revolution of the receiving reel takes up more cable than can be covered by the wires being 55 applied thereto, then a slippage results between the shaft 28 and grooved wheel 37 so that the revolution of the receiving reel to wind the cable thereon is checked. This is necessary because of the fact that as the machine 60 operates, the coil of cable upon the supply reel constantly grows less, and the coil of cable upon the receiving reel constantly grows greater, and hence if the driving mechanism for rotating the receiving reel to wind the cable is so timed as to pull

the cable through the machine with proper speed at the start of the operation of the machine, it will obviously increase the amount of cable pulled through as the coil of cable upon the receiving reel grows 70 greater. Accordingly there must be a slippage provided for the driving means of the receiving reel, or the feed of the cable through the machine at times in the operation thereof, will be faster than the wires 75 can be wrapped about the same, thereby producing an inefficient product. Transmission of the power from the screw 35 to the trunnions 31 is effected by a worm gear 38 mounted on a stub shaft 39, (see Fig. 6), 80 which stub shaft carries a bevel gear 40, meshing with a bevel gear 41, secured onto a vertical shaft 42, on the upper end of which shaft is a bevel 43, meshing with a bevel 44, secured to the trunnions 21. 85

It is desired that the operator have it within his power to increase the friction or binding engagement on the grooved wheel 37 to place a frictional retarding force on said wheel and to withhold it against its 90 tendency to rotate with the shaft 28 and by such retarding force create a slippage between the shaft and the wheel. In the construction shown a band 45 is placed in the groove of the wheel 37, which band is connected to a cable 46, secured around a stub shaft or trunnion 47, which in turn is joined to an arm 48, and this arm is connected to a cable 49 secured to a drum 50, which drum may be turned through any suitable means 100 by the operator. As the drum 50 is turned the cable 49 is drawn upward raising the arm 48, revolving the trunnion 47, winding up the cable 46, which places a tension upon the strap 45 which creates a friction on the 105 grooved wheel 37 thereby exerting a retarding force on this wheel and the gear 35, so that slippage is brought about between the wheel 37, gear 35 and the shaft 28.

The foregoing describes the means of 110 feeding the cable through the machine and turning it about its axis during such feeding movement. The armor laid on the cable comprises inner wires 51 and outer wires 52, which, as stated in the preamble of the 115 specification, are fed into the machine in duplicate so as to make a double wrapping of both the inner and outer layers of wires. The wires 51 are fed into position by feed rolls 53, while the wires 52 are fed in by 120 feed rolls 54 and 55. These latter feed rolls also act as die members to flatten one side of the wire prior to its application onto the cable. The wires are forced through a guiding block 56 and into engagement with 125 the grooved surfaces of rotatable die members 57, of which in the construction shown there are three. Each die member is formed with an upper grooved surface 58 and a lower grooved surface 59, the former 130

effecting a turning of the inner wires and the latter a turning of the outer wires. The cable 60, as shown, passes centrally of the dies 57; that is the outer periphery of each die is spaced apart a distance from the periphery of the cable, the dies being grouped or arranged centrally about the cable.

As the wire is forced into engagement with the grooved surface of the dies, it is bent into spiral formation by moving from one die onto the other, and by revolving the cable as it passes downward, the wires are wrapped or coiled about it; the inner wires being first laid and the outer wires next laid, with said outer wires breaking joints with the turns or wraps of the inner wire. This feed mechanism and die mechanism is now known in the art, and is not claimed as a portion of the present invention.

As showing a means for driving the feed rolls, I provide a gear 61 which is affixed to the shaft 25. This gear meshes with a gear 62 fixed on a stub shaft 63. Mounted on said stub shaft is a pinion 64 meshing with a gear 65 on a stub shaft 66. On this latter shaft is mounted a gear 67 meshing with a gear 68 which meshes with a gear 69. The gear 69 is mounted co-axially with a gear 70 which meshes with a gear 70^a connected to a shaft 71, on which the feed roll 54 is mounted. The gear 67 also meshes with a gear 72 which is connected to a shaft 73, on which the feed roll 55 is mounted. The gear 67 also meshes with a gear 74 which meshes with a gear 75. This gear 75 meshes with a gear 76 secured to a shaft 77, upon which is mounted the feed roll 53. This method of driving will be understood from Figs. 8 and 9, and as shown in Fig. 8, there is both an upper and lower set of gears for driving the shafts 71, 73, and 77. This, however, is merely to increase the driving power of the gearing. There are also feed rolls complementary to the rolls 53, 54, and 55 mounted on the shafts 66^a, 66^b, and 66, respectively. No positive means are provided for rotating the die members 57, these being rotated by the forcing of the wire into engagement therewith.

The operation is thought to be clear from the foregoing, but briefly is as follows: The cable is coiled upon the supply reel. One end is pulled down and affixed to the receiving reel. The machine is started and the reels are revolved about their respective trunnions as centers, causing the cable to pass from the supply reel onto the receiving reel, which gives the cable the longitudinal movement through the machine; and at the same time the supply reel and receiving reel are revolved simultaneously at right angles to their center of revolution, so as to give the cable a turning movement about its longitudinal center as it is fed through

the machine. The wires are fed in by the feed rolls 53, 54, and 55 and forced into engagement with the grooved surfaces of the die members, and are turned to form inner and outer layers on the cable, and by the turning movement of the cable are coiled about the cable to form the armor. As the operation of the machine progresses, friction may be applied to the revolving mechanism for the receiving reel by the operator actuating the drum 50, so that a slippage is produced between said mechanism and reel insuring a proper and uniform feed of the cable through the machine at all periods of the operation.

We claim:

1. In a cable armoring machine, the combination of two frames arranged to revolve about a common axis, a shaft on which each frame is mounted, means connected with each shaft for revolving the frames in unison, a cable supply reel mounted in one frame and a cable receiving reel mounted in the other, each reel being arranged to revolve in its frame about an axis at right angles to the frame axes, whereby the cable is revolved as it passes from one reel to the other, means for revolving the receiving reel about its axis at variable speeds, and means between the two reels connected with the frame revolving means for applying armor to the cable at a fixed speed relative to the revolving speed of the cable, the engagement of the armor with the cable serving to control the feeding movement of the cable to a fixed speed relative to its revolving speed, substantially as described.

2. In a cable armoring machine, the combination of two rotatable reels, one for supplying and the other for receiving cable, means for turning the said reels about an axis perpendicular to their axes of rotation, whereby the cable is revolved as it is fed, and means connected with the reel turning means for armoring the cable, the said means cooperating with the armor to control the feeding movement of the cable to a fixed speed relative to its speed of rotation, substantially as described.

3. In a cable armoring machine, a receiving reel, a frame within which the reel is rotatably held, a rotatable shaft secured to the frame, and means for causing the reel to be rotated within the frame at variable speeds, comprising a transmission shaft carried by the reel frame, bevel gears connecting one end of the transmission shaft with the reel, a worm and gear, the former frictionally held, connecting the other end of the transmission shaft with the frame shaft, and pawl mechanism for applying friction to the frictionally held worm to retard its movement as desired, whereby the receiving reel may be revolved at variable speeds, substantially as described.

4. In a cable armoring machine, the combination of cable supply and receiving reels, mountings for the reels, means for rotating said mountings at equal speeds to impart a 5 rotating movement to the cable passing between them, means for imparting a winding tension to the receiving reel to take up the completed product as it is delivered, means for feeding an armor onto the cable in heli-

cal formation, and power transmission for 10 operating the armor feeding means at a speed commensurate with the rotation of the cable, substantially as described.
